UNITED STATES PATENT OFFICE.

LEWIS D. EWING, OF AKRON, OHIO.

VENTILATED FIREPROOF WALL.

No. 849,776.

Specification of Letters Patent.

Patented April 9, 1907.

Application filed May 26, 1905. Serial No. 262,459.

To all whom it may concern:

Be it known that I, LEWIS D. EWING, a citizen of the United States, residing at Akron, in the county of Summit and State of Ohio, have invented certain new and useful Improvements in Ventilated Fireproof Walls, of which the following is a specification.

My invention relates to improvements in ventilated fireproof walls, and pertains more particularly to the construction of such walls of blocks of concrete or cement.

The object of the invention is the provision of a building-wall which shall be fireproof, which shall be ventilated and open to the atmosphere under certain limits, but provided with means for excluding all other objects or things than the air, which will be comparatively inexpensive in first cost, strong, durable.

20 A further object is to protect the inner portions of the building-wall from outside atmospheric effect due to the conditions of the weather.

With these objects in view the invention 25 consists of a building-wall constructed of cement or concrete blocks formed with a plurality of portions, as the outer and inner portions, an outer, an intermediate, and an inner portion, or an outer, an inner, and an intermediate double portion. In all the forms the blocks are so arranged and constructed that ventilation is provided to the atmosphere by vertical and horizontal air-passages, the vertical passages extending upwardly through the wall and the horizontal passages connecting at certain intervals with the atmosphere. The wall is further provided with air-retaining cells independent of the ventilating-passages for rendering the 30 wall a non-conductor of heat and cold within limits, these cells being located in the innermost wall portion. In addition to the ventilating air passage-ways and the air-retaining cells I provide a multiplicity of air-chambers located centrally of the wall for further insulating the wall against heat or cold.

45 The blocks are provided with interlocking joints which will facilitate the application of mortar and assure a tight joint and also with convenient projecting portions and recesses to form convenient holds for handling the same.

50 By the construction of the wall as herein-after disclosed it is practically impossible for dampness to be inducted therethrough by capillary attraction, as it will be observed

that the blocks forming the outer portion of the wall are almost entirely separated from the blocks forming the inner portion of the wall by air-spaces.

60 In the drawings I have illustrated one example of the physical embodiment of my invention and two modifications thereof.

Figure 1 is a top plan view of one of the building-blocks, said view being divided by a line, the half at the left representing a portion of a block used in the outer portion of the wall and the half at the right in said view indicating a portion of the block employed in constructing the inner portion of the wall. 70 Fig. 2 is a top plan view of a filler-block, which when used is located centrally of the wall to increase the area thereof. Fig. 3 is an end view of the block shown in Fig. 2. Fig. 4 is an inner side view of the outside face 75 block. Fig. 5 is a side view of the intermediate filler-block shown in Fig. 2. Fig. 6 is an end view of the block shown in Fig. 1. Fig. 7 is a sectional view of part of a wall constructed with two intermediate rows of filler-blocks located between the outer and inner face-blocks. Fig. 8 is a sectional view of a portion of the wall constructed of the outer face and inner face blocks, omitting the filler-blocks. Fig. 9 is a sectional view of a part of 80 a wall, showing one row of intermediate filler-blocks located between the outer and inner face-blocks. Fig. 10 is an exterior broken face view of a portion of the wall embodying my invention; and Fig. 11 is a transverse vertical section of a portion of a wall on line *a a*, 85 Fig. 10.

90 Referring to the drawings, the exterior face-blocks are designated by the numeral 1. These blocks are provided with an outer 95 elongated side which when the blocks are assembled form the face or front of the building. The projections 2 2 of the sides are connected to the inner shorter sides by oblique faces 3 3, which faces are provided 100 with recesses 3' 3' for convenient handholds. At the junction of the shorter side with the oblique surfaces 3 an angular portion 4 is fashioned, which angle forms one of the members of the interlocking joint by which the blocks 105 are held together. As clearly shown in Figs. 6 and 11, a groove 5 is formed on the under surface of the block at either side thereof for the reception of mortar and to increase the effectiveness of the bond between the blocks. The block has openings 110 or passages extending vertically there-

through, as indicated at 7 7 7, which when the blocks are assembled in the wall form air-ventilating passages.

In Fig. 8 of the drawings the simplest form of the embodiment of my invention is illustrated, and in this view the above-described outer face-block is employed in conjunction with the inner face-block 8. This inner face-block closely resembles the outer face-block in outline, having complementary projections 8' 8'', oblique surfaces 9 9, recesses 9' 9'', angle portions 10 10, and longitudinal grooves 11 11 in its under face. The ventilating air-passages of block 1 are not present in the inner face-block 8; but instead I form the cavities 12 and 12' 12'', which extend into the block from the bottom and act as air-cells, thus providing a multiplicity of air-cells or air-space in the inner portion 20 of the wall of the building.

The face view, Fig. 10, and sectional view, Fig. 11, illustrate the assembled blocks forming the building-wall. The wall is topped out with a frieze 13, and the blocks 25 forming the frieze are provided with openings or holes 13', extending vertically therethrough, which form continuations of the ventilating passage-ways 7 of the outer face-block, and these vertical passages have 30 an outlet through the horizontal passages 13'', which are open to the atmosphere. The face of the frieze may be provided with a variety of ornamental work to suit the fancy, and these openings located, as may 35 be desired, to afford an outlet to the atmosphere from the ventilating-passages formed in the outer portion of the wall.

The water-table 14, which is imposed upon the foundation 15 of the building-wall, projects a suitable distance beyond the line thereof and is provided with apertures 16, opening outwardly at the under side thereof and forming a continuation of the ventilating-passages of the outer portion of the wall 40 and connect the ventilating-passages with the atmosphere. Thus I provide a continuous ventilating-passage having openings at the top and bottom thereof to the atmosphere for free circulation of the air there-45 through. Another form of communication with the atmosphere at the bottom of the ventilating passage-way may be utilized by providing an ornamental lattice-work panel 17 with atmospheric openings 17' and vertical passage 18, the panel being supported by the sill 19. Screens 20 may be provided to exclude birds, &c.

In building the wall the blocks 1 are assembled so as to break joints, as shown in 60 Figs. 7, 8, 9, 10, and so arranged that the joint of adjacent blocks of the lower of two horizontal layers of blocks will be equidistantly overlapped on top by a block of the upper of said layers, and when the blocks 65 are so located the openings 7 and 7' 7'' ex-

tending through the upper block are located over the space formed in the lower of said layers between adjacent blocks, with part of said openings in the upper block extending over part of the openings 7 7' 7'' of the two 70 lower adjacent blocks, thereby establishing communication laterally and vertically through the interior portion of the outer face of the wall.

The blocks employed in constructing the 75 inner face of the wall are assembled so as to break joints and arranged so that the joint of adjacent blocks of the lower of two horizontal layers will be equidistantly overlapped on top by a block of the upper of said 80 layers. Thus the cavities 12 12' 12'' are located over the space formed in the lower of said layers between adjacent blocks, thereby forming air-retaining cells between the said layers.

The mortar placed between the conjoining sides of adjacent layers of blocks provides sufficient space to allow for a slight circulation of air between the air-retaining cells to provide for contraction and expansion of the 90 air contained in the cells.

It will be observed that the outlines of the outer and inner blocks are such that they extend from either face of the wall inwardly beyond the inner line of the blocks forming 95 the opposite face of the wall and overlap the lower block of two adjacent layers of block, thereby forming a bond between the two faces of the wall.

Figs. 7 and 9 illustrate the application of 100 the principles of my invention, wherein it is desired to increase the width of the walls of a building. Referring to Fig. 7, if an extreme width of wall is required, I employ a number of courses of filler-blocks 21 in conjunction with the outer and inner face-blocks 1 and 8. Each of these filler-blocks has an angular portion 21', adapted to interlock with the angle portions 8' of the inner face-block in some instances, and to interlock with each other at the center of the wall, and also to interlock with the angular portions 4 of the outer face-block. Thus when assembled the two face-blocks and the intermediate or filler blocks are tightly jointed 110 together, and the wall is bonded together by the overlapping of the upper blocks of adjacent layers of blocks. Air spaces or cells 22 are formed in the blocks 21, and spaces 23 are left between the adjacent 115 blocks.

Referring to Fig. 9, when a medium wall is desired I utilize one row of filler-blocks 21, the construction of which will be apparent from an inspection of the drawings.

From the above description it will readily be understood that I have provided a building-wall which will cover the objects and purposes set forth. The air passing through the ventilators in the outer face of the wall is 130

valuable in damp weather, as the presence of the air greatly assists in drying out any dampness that may accumulate therein and keeps the inner portion of the wall in a dry condition. In warm weather the currents of air in the ventilating-passages keep the inner portion of the wall and contained air-cells in a cool state as compared with the sun-heated air on the outside, as the heated air in the ventilators passes out at the top of the wall and is replaced with comparatively cooler air drawn in from below. In cold and stormy weather the outer portion of the wall shields the inner portion thereof with its air-cells from the rain, sleet, and storms, and the air-currents absorb the moisture which may penetrate the outer portion to the ventilating-passages.

The air-cells in the interior face of the wall are beneficial in cold weather in that they retain the air that has become warmed by interiorly-generated heat induced inwardly through the inner face of said wall, forming a warm-air zone within the wall.

Having thus fully described my invention, what I claim, and desire to secure by Letters Patent, is—

1. A building-block having parallel long and shorter sides, oblique ends connecting said sides, interlocking lugs formed at the ends of the shorter side, and ventilating-passages formed entirely through the block.

2. A building-block having parallel long and shorter sides, oblique ends connecting said sides, locking-lugs at the ends of the shorter sides fashioned to form interlocking means, extensions formed on the ends of the longer sides, and openings extending vertically through the block.

3. A building-block having a long and short side, oblique ends connecting said sides, a locking-lug at the ends of the short side and a recess formed by each lug and the oblique ends, and plane extension projecting beyond the body of the block at each end of the long side.

4. A building-block having parallel long and short sides, the ends of the body of the block formed on oblique lines, angular locking-lugs projecting from the ends of the short side, extensions formed at the ends of the long side of a thickness of one-third of the body of the block, and vertical passages extending through the block.

5. A wall comprising an inner and an outer series of blocks each fashioned to extend inwardly beyond the inner line of the opposite series, continuous vertical passages formed in the outer series of blocks, and each block of each series having parallel long and short sides, and interlocking lugs formed at the ends of the short sides.

6. A building-block having a long and a short side, oblique ends connecting said sides, a V-shaped interlocking lug at the ends

of the short side and a recess formed by each said lug and the oblique ends of the block, and plane extensions projecting beyond the body of the block at each end of the long side.

7. A wall comprising an exterior and an interior series of blocks, the blocks of each series alternating and arranged to extend inwardly beyond the inner line of the blocks of the opposite series, locking-lugs on the adjoining blocks of the two series, extensions formed at the ends of the blocks of each series, and ventilating-passages formed in the outer series of blocks.

8. A wall comprising an inner and an outer series of blocks fashioned to extend inwardly beyond the inner line of the blocks of the opposite series, continuous vertical passages formed in the outer series of blocks, an upper friezework communicating with said passages and a water-table near the bottom of the wall communicating with the lower end of the passages, the blocks in each series each having a parallel long and short side, oblique ends connecting said sides, locking means formed at the ends of the shorter sides, and extensions formed at the ends of the long sides.

9. A wall comprising an exterior and an interior series of blocks, the blocks of each series alternating and arranged to extend inwardly beyond the inner line of the blocks of the opposite series, each of said blocks having a long and a short side, locking-lugs formed at the ends of the short side, and extensions formed at the ends of the long sides of the blocks providing an air-space within the wall, and mortar-retaining grooves on a surface of each of the blocks.

10. A wall comprising an inner and an outer series of blocks each of said blocks having a long and a short side, an intermediate block having locking-lugs at its corners, and complementary lugs formed at the ends of the short sides of the blocks in the inner and outer series to engage the lugs on the intermediate blocks.

11. In a building-wall an exterior series of blocks and an interior series of blocks, the blocks of each series having a long and a short side and oblique ends connecting said sides, a locking-lug at the ends of the short side of each block adapted to fit a complementary lug on the adjoining block, and plane extensions projecting beyond the body of the blocks at the end of the long sides.

12. In a building-wall an exterior series of blocks and interior series of blocks, the blocks of each series having a long and a short side and oblique ends connecting said sides, a V-shaped interlocking lug at the ends of the short side of each block adapted to fit a complementary lug on the adjoining block, and extensions projecting beyond the body of the blocks at each end of the long sides.

13. In a wall construction, a filler-block having parallel sides and apex-formed ends, openings extending vertically through the blocks and oblique interlocking lugs formed 5 at the ends of the sides.

14. In a wall construction, an exterior series of blocks having parallel long and short sides, oblique ends connecting said sides and said blocks formed with openings forming 15

16. ventilating - passages communicating with the atmosphere, an interior series of blocks having parallel long and short sides, oblique ends connecting said sides, said block formed 20

with cavities forming air-cells interiorly of the inner portion of the wall, and a central block having parallel sides, apex-formed ends, and openings extending vertically through the said block to form air-chambers disposed interiorly of and independent of the ventilating-passages and air-cells.

In testimony whereof I affix my signature in presence of two witnesses.

LEWIS D. EWING.
